UNITED STATES PATENT OFFICE.

JACOB H. FLEISCH, NEW YORK, N. Y.

DESIGN FOR A NECKTIE.

SPECIFICATION forming part of Design No. 17,039, dated December 28, 1886.

Application filed October 7, 1886. Serial No. 215,637. Term of patent 7 years.

To all whom it may concern:

Be it known that I, JACOB H. FLEISCH, a citizen of the United States, residing at New York, in the county of New York and State 5 of New York, have invented and produced a new and original Design for Neckties, of which the following is a specification, reference being had to the accompanying drawings, forming part thereof.

10 In the accompanying drawings, Figure 1 illustrates an ordinary bow-tie, the ends of which present a ribbed appearance. Fig. 2 is a modification.

15 The leading feature of my design consists in ribs running transversely over a portion of the necktie, the remaining portion of the surface thereof being plain.

A represents a bow-tie of the ordinary form, composed of gros grain, satin, or other suitable smooth fabric of which it is customary to manufacture neckties. The ends or flaps B of the tie (shown in Fig. 1) are transversely ribbed, from a half to an inch and a quarter in width, the ribbed portion being broad or 25 narrow, coarse or fine, according as the tie is of a large or small size, and giving to the tie a transversely corrugated or ribbed appearance. In the modification shown in Fig. 2

the plain and corded portions are reversed, in this case the ends or flaps B being plain, while 30 the rest of the tie presents a ribbed appearance.

It will be observed that ties of the above design present a very pleasing appearance, the parts having a contrast without necessarily 35 any variation of colors.

Having fully described my design, what I claim as new, and desire to secure by Letters Patent, is—

1. In a design for neckties, the ornamentation of the same, consisting, essentially, in ribs running transversely over a portion of the tie, the remainder of the surface thereof being plain, substantially as shown and described. 40

2. The design for neckties herein shown 45 and described, the ends of which are transversely ribbed and the middle portion plain, substantially as set forth.

In testimony whereof I have signed this specification in the presence of two subscribing 50 witnesses.

JACOB H. FLEISCH.
